PHONOGRAPH

Meyer Lehman, New York, N. Y.

Application April 13, 1935, Serial No. 16,142

5 Claims. (Cl. 274—18)

This invention relates to improvements in phonographs and particularly to multi-disc record and electrical reproducing machines wherein the records are successively removed from 5 the turntable after being played.

In order to construct a portable phonograph of the mentioned type in as small and compact a manner as possible, it has been necessary, heretofore, to provide a collapsible record receiving device which was opened and hung on the outer side of the case which housed the mechanism and the played records were successively ejected into said receiving device. Since this device was outside the case, the cover therefor, of 10 necessity, had to remain open during operation of the phonograph.

This latter condition, essentially, was faulty, since needle scratch and other extraneous noises provided undesirable background noises to the 15 recorded sound which emanated from the electrical reproducing means.

It is desirable therefore and is an object of the invention, to provide means whereby the phonograph case may be completely closed over 20 the playing mechanism while in operation to deaden and eliminate these undesirable sounds, yet permitting the records to be ejected from the case into the receiving tray on the outer side thereof.

30 While the invention is more particularly applicable to portable machines, it, of course, may be utilized in larger machines where it is desired to conserve space when out of use.

The invention further contemplates the provision 35 of a compact self-contained phonograph in which the receiving tray may be conveniently housed in the cover thereof to form a compartment for disc records.

With the above and other objects in mind, 40 the invention resides in the novel features of construction described in the following specification and illustrated in the drawing, in which:—

Fig. 1 is a perspective view of a portable 45 phonograph as contemplated in this invention.

Fig. 2 is a plan view, partly broken away, showing details of construction.

Fig. 3 is a vertical sectional view as taken on the line 3—3 of Figure 2.

Fig. 4 is a front view of a phonograph, partly 50 in section, showing an alternate form of the invention.

Fig. 5 is a fragmentary detail of an alternate form of the invention.

The phonograph comprises a case 5 in which, 55 in the usual manner, is housed the mechanism

for operating the turntable 6 and the reproducing apparatus eventuating in a speaker located behind the opening or grill 7 in the case.

The casing 5 is provided with a table 8 on which is supported the turntable 6, a reproducer 5 arm and pickup (not shown), means to eject a record, and such other devices and controls germane to this type of apparatus.

The ejector means here illustrated comprises an arm 9, mounted to swing horizontally on a 10 post 10 approximately half way across the stack of records "S" and mechanism located beneath the table 8 elevates the free end of arm 9 as it swings in this manner.

The arm 9, at its free end, is provided with 15 means 11 to engage the rim of the topmost record of the stack so, as the arm is elevated, the record is raised as shown in Figure 3 to free it from the turntable spindle 12.

The post 10 is provided with a bracket or the 20 like 13 carrying an arm 14 which swings horizontally with the movement of the ejector arm. This arm 14 is arranged to engage against the inner face of a hinged flap 15 carried by the cover 16 of the case 5 in a manner whereby an 25 opening 15^a is provided for the passage of a record R from the stack S to a position in a tray 17 attached outside the case 5, by engagement in loops 18 of hooks on the tray 17.

This tray, when not used as such, is positioned 30 within the cover 16 to provide a compartment 19 in which records may be stored.

When not in use the phonograph appears as shown in Figure 1. When it is desired to play the machine, the cover 16 is raised and a stack 35 of records placed on the turntable 6. The pickup is placed on the topmost record in the usual manner, the turntable started rotating and the cover closed, the tray 17, of course, first being removed from the cover and hooked into place 40 as shown in Figures 2 and 3, by engaging the tray carried hooks into the loops 18.

It will be noted that since the turntable, records and pickup are completely enclosed, all foreign noises such as needle scratch, etc., are 45 deadened and only the reproduced recording on the record emanates from the grill 7.

When the topmost record is completely played 50 mechanism is set in motion to raise said record as described by means of the arm 9, and to be pushed towards the flap 15; however, the arm 14 is positioned to engage this flap before the record does so to tilt it open so on completion 55 of the rotation of the ejector arm 9 the space 15^a

is provided for the passage of the record to the tray 17.

As the arm 9 returns to its initial position, the arm 14 releases the flap so it may return to its 5 normal closed position as shown in Figure 4.

The next topmost record is played and the action continues as heretofore until all the records on the turntable are played.

An alternate form of construction shown in 10 Figure 5 comprises constructing the flap 20 as a soft pliable member which may be engaged by the oncoming edge of the record as it is being ejected, the flap then dropping back into place as shown by the dot-dash lines. In this case the arm 14 15 may be dispensed with.

The mechanism for ejecting the record forms no part of the present invention and is for illustration only. Many different forms of record removing and ejecting means are in commercial 20 use and it is intended that the present invention may be used with any form of such device. While the invention has been illustrated as being applied to a device expelling the records from one side of the phonograph, it will be obvious that 25 the invention may be applied to or associated with devices which eject or expel records from the rear, front or either side of the phonograph.

It will also be seen that the flap 15 may be 30 hinged vertically to swing as a door, and in such case, it could be held open or allowed to remain open during operation of the phonograph, thus providing an unobstructed open space for the passage of expelled records.

As can be seen from the foregoing, a simple 35 device for the purpose intended is provided in its preferred embodiments and since immaterial changes in construction may well be made without departing from the scope of the invention as set forth in the following claims, interpretation 40 thereof should be made only in the light of the prior art.

Having thus described my invention, what I claim as new and desire to secure by Letters Patent, is:

45 1. A multi-disc record phonograph having means for ejecting the topmost record of a stack of records carried by the phonograph turntable, said phonograph being adapted to be completely enclosed when played and comprising a casing 50 forming said enclosure, a swingable flap forming part of one wall of said casing, a record receiving member carried by and without the casing, said

flap being normally closed but automatically operable by the record ejecting means just prior to the ejection of a record to provide passage space for the record ejected from the phonograph into said record receiving member. 5

2. A multi-disc record phonograph having means to eject the played topmost record of a stack of records carried by the phonograph turntable, said phonograph being adapted to be completely enclosed when played and comprising a 10 casing forming said enclosure, a vertically swingable flap forming part of one wall of said casing, a record receiving member carried by and without the casing adjacent the lower edge of said flap, and means operable by the record ejecting means, upon ejection of a record, for swinging said flap from its normally closed position to provide passage space for the ejected record to slide into said record receiving member. 15

3. In a multi-disc record phonograph having means for ejecting the played topmost record of a stack of records carried by the phonograph turntable, a casing, a swingable flap forming part of one wall of said casing, and an arm carried by and operable with the ejecting means for moving 20 said flap into an open position in advance of a record being ejected to afford passage space therefor. 25

4. In a multi-disc record phonograph having means to cast off and eject the topmost record 30 of a record stack carried by the turntable, a case for the phonograph, the case having an opening for the passage of records therethrough, a flap hinged at its top to the casing and normally closing said opening, and means operable by the 35 cast-off and ejecting means to move said flap away from the opening in advance of the record being ejected, to provide passage space for said record.

5. The combination with a multi-disc record 40 phonograph having means to cast off and eject from its casing the topmost record of a record stack carried by the turntable, a case for the phonograph, said casing comprising a plurality of hinged sections adapted normally to be positioned to completely enclose the phonograph, and means associated with the cast-off and ejecting means, operable automatically when a record is about to be ejected, to swing one of the sections on its hinges to produce an opening in 50 the casing for passage of a record therethrough. 45
